UNITED STATES PATENT OFFICE

165,834

CUP

Charles N. Gardner, Suitland, Md.

Application February 7, 1951, Serial No. 14,120

Term of patent 14 years

(Cl. D44—9)

To all whom it may concern:

Be it known that I, Charles N. Gardner, a citizen of the United States, residing at Suitland, in the county of Prince Georges and State of Maryland, have invented a new, original, and ornamental Design for a Cup, of which the following is a specification, reference being had to the accompanying drawings, forming a part thereof.

Figure 1 is a perspective view of the cup, showing my new design; and

Figure 2 is a front elevational view thereof.

The dominant features of the design reside in the arcuate hood portion providing a tapered shoulder on the front of the cup at the juncture of the differently inclined upper and lower wall sections which form a circular line of demarcation that coincides with the base line of the shoulder

and terminates the arcuate line of mergence of this shoulder with the body of the cup, as shown.

I claim:

The ornamental design for a cup, substantially as shown and described.

CHARLES N. GARDNER.
